UNITED STATES PATENT OFFICE.

WALDEMAR KOPS, OF NEW YORK, N. Y., ASSIGNOR TO KOPS BROS. INC., OF NEW YORK,
N. Y., A CORPORATION OF NEW YORK.

APPAREL GARMENT.

Application filed December 24, 1925. Serial No. 77,467.

My present invention relates to an apparel garment and particularly to a garment of the brassière type. As is generally understood, due largely to the prevalent use 5 of extremely low busted corset garments, there is a tendency for the flesh to overlie the upper edge of the corset not only at the front but also at the side portions of the body of the wearer. This not only produces an uncomfortable but oftentimes an 10 unsightly effect. The object of the present invention is the provision in a garment of the type described of both a front or diaphragm control strap and also straps at the 15 sides of the garment to prevent the flesh from overhanging the upper edges of the corset at these portions of the body, and the construction of the garment will be hereinafter more particularly described.

20 In the drawing Figure 1 is a perspective view illustrating a garment made in accordance with my present invention, and

Fig. 2 is an elevation of the garment viewed from the inner side thereof.

25 By reference to the drawing it will be seen that the garment made in accordance with this invention includes a front member 10, back members 11 and 12, and side members 13 and 14, and 15 and 16. Between the front member 10 and the side members 13 and 15 there are reinforcing strips 17 and 18. Similarly between the side members 13 and 14 there is a reinforcing strip 19, and between the side member 14 and the back member 30 11 there is a reinforcing strip 20. In like manner on the other or right side of the garment, between the side members 15 and 16 there is a reinforcing strip 21, and between the side member 16 and the back member 12 35 there is a reinforcing strip 22. There is also a reinforcing strip 23 at the edge of the back member 11 and a reinforcing strip 24 at the edge of the back member 12. The garment is connected in position on the 40 body, in the form of the invention as illustrated, by a series of spaced eyelets 25 suitably connected to the reinforcing strip 23 and similar series of spaced hooks 26 connected to reinforcing strip 24.

45 Underlying the front member 10 I employ a strap 27 which is preferably so constructed that the upper edges incline upwardly and are connected by a line of stitching or otherwise to the front member.

50 The upper portion of this strap 27 is also

preferably connected to the front member by lines of stitching indicated at 29 so as to cause this portion of the strap to function as a flesh controller at the front of the garment and over the diaphragm of the 60 wearer. The lower edge of the strap 27 is also tapered with the edge portions thereof extending downwardly. This lower edge 30, however, is not secured to the overlying portion of the front member 10. Secured 65 to the lower front portion of the strap 27 there is a tape 31 fitted with a clasp 32 and a hook 33, the hook 33 being adapted to engage either one of a series of eyelets 34 provided for this purpose in the lower front 70 central portion of the front member 10, and the clasp 32 to engage a fastener of a corset or other undergarment to exert a downward tension in the strap 27 and also to assist in maintaining the garment in position on the body of the wearer.

75 In the left hand side of the garment there is a flesh retaining strap 35. This extends from the reinforcing strip 17 to the reinforcing strip 20 and the parts thereof preferably incline upwardly or toward the top of the garment from the reinforcing strip 17 to the reinforcing strip 19, and in the opposite direction or downwardly from the reinforcing strip 19 to the reinforcing strip 80 85 20. The flesh retaining strap 35 is secured to the reinforcing strip 19 from the upper central portion thereof as indicated at 36 to a position approximately midway of the width of the strap as indicated at 37, the forward end of the strap being connected to the reinforcing strip 17 and therefore to both the front member 10 and the side member 13, while the rear end of the strap is connected to the reinforcing strip 20 and 90 therefore to the side member 14 and the back member 11.

95 In the right hand side of the garment there is a complementary flesh retaining strap 38. This strap extends from the reinforcing strip 18 to the reinforcing strip 22 and the part thereof between the reinforcing strip 18 and the reinforcing strip 21 preferably inclines upwardly, while the other part thereof preferably inclines in 100 the opposite direction or downwardly between the reinforcing strip 21 and the reinforcing strip 22. This strap 38 is connected to the reinforcing strip 21 from the upper central portion thereof as indicated at 39 105 110

to the point as indicated at 40 which is approximately midway of the width of the strap. At its forward end this strap is connected to the reinforcing strip 18 and at 5 its rear end to the reinforcing strip 22. Otherwise than as specifically described, the flesh retaining straps 35 and 38 are not connected to the overlying portions of the garment. Also as illustrated, the strap 35 may 10 be provided with series of stitch lines 41 in the upper portion thereof and stitch lines 42 in the lower portion thereof. Similarly the strap 38 may be provided with series of stitch lines 43 in the upper portion there- 15 of and stitch lines 44 in the lower portion thereof, these stitch lines running substantially parallel with the upper and lower edges of the straps.

Also as illustrated, the lower side portions of the garment may be fitted with inserts 45 and 46 of elastic material so as to cause the garment to conform to the body and the underlying garment. Furthermore, the garment may also be provided with suitable shoulder straps 47 and 48.

The reinforcing strips 19 and 21 lie at approximately the axillar lines of the garment and from the construction of the garment as hereinbefore described it will now 30 be understood that the flesh retaining straps 35 and 38 with the intervening strap 27 comprise a substantially continuous flesh retaining belt which extends entirely across the front portion of the body and appreciable distances to the rear of the axillar lines thereof so as to retain and maintain in position the flesh which would otherwise extend beyond or overlie the upper edge of the corset garment.

40 I claim as my invention:

1. In an apparel garment of the type described, a front member, side members, back members, means for securing the garment on the body of the wearer, a diaphragm strap underlying the front member being substantially coextensive therewith circumferentially of the garment and connected along its upper edge to the overlying portion of the front member of the garment, and side flesh retaining straps each extending from the said diaphragm strap across a corresponding side member and upwardly

from the diaphragm strap to substantially the axillar line of the corresponding side member and then downwardly to the rear of the side member and each of the said side flesh retaining straps being connected to the corresponding side member from the upper edge thereof at the axillar line to a point along the axillar line substantially distant from the upper edge of the corresponding side flesh retaining strap and having its upper and lower edges free from the body of the garment, the said diaphragm strap and side flesh retaining straps being adapted to 60 65 70 75 80 85 90 95 100 overlie the upper edge of an undergarment to retain the flesh which would otherwise overhang the same.

2. In an apparel garment of the type described, a front member, side members, back members, means for securing the garment on the body of the wearer, a diaphragm strap underlying the front member being substantially coextensive therewith circumferentially of the garment and connected along its upper edge to the underlying portion of the front member of the garment, side flesh retaining straps each extending from the said diaphragm strap across a corresponding side member and upwardly from the diaphragm strap to substantially the axillar line of the corresponding side member and then downwardly to the rear of the side member, each of the said side flesh retaining straps being connected to the corresponding side member from the upper edge thereof at the axillar line to a point along the axillar line substantially distant from the upper edge of the corresponding side flesh retaining strap, the said diaphragm strap and side flesh retaining straps being adapted to overlie the upper edge of an undergarment to retain the flesh which would otherwise overhang the same, and a gore member set in the lower axillar portion of each side member, each elastic gore extending approximately from the lower edge of the corresponding side flesh retaining member to the lower edge of the said member in which it is fixed.

Signed by me this 9th day of December, 1925.

WALDEMAR KOPS.
